2,049,277

DEWAXING AND PARTIALLY DECOLORIZING PETROLEUM LUBRICATING STOCK

Claude F. Tears, Warren, Pa., assignor to The Petroleum Processes Corporation, Wichita, Kans., a corporation of Kansas

Application July 16, 1935, Serial No. 31,567

7 Claims. (Cl. 196—17)

This invention relates to the dewaxing and decolorizing of petroleum lubricating stocks. Particular objects of the invention are to simplify and reduce the costs of these operations; to reduce the number of steps or stages required for accomplishing these particular purposes; to eliminate the requirement for certain preliminary treatment heretofore found necessary; to accomplish finer or closer separation between oil and waxy layers and to effect all these new and desirable results in a thoroughly practical way.

Other objects and the details of construction and operation by which such objects are attained are set forth in detail or will appear in the course of the following specification.

In operation of the processes disclosed in the Tears Patents Nos. 2,000,427 and 2,008,570, it was found that these had certain advantages for processing heavy residual lubricating stock such as steam refined stock and long residuum from Pennsylvania crude, which did not appear in the original work on the subject. In known dewaxing processes, it is the usual practice to operate on a charging stock that has been partially decolorized or acid treated, or de-asphaltized, or to operate on a distillate stock such as would be obtained by vacuum distillation of topped crude. The charging stock in other words has normally been subjected to some preliminary treatment for removal of color bearing constituents, asphalt and inhibitors which prevent the formation of wax structures that can be separated from the oil by known means.

In conventional refinery practice, that is, when wax is removed by cold settling or by centrifuging, it is always essential to decolorize before dewaxing. In the usual cold settling operation, a product that has not been decolorized will not settle to give satisfactory separation of wax and oil. In dewaxing by centrifuging, an undecolorized stock results in a wax formation of such consistency that it can not be discharged satisfactorily from the centrifuge bowl.

In the more modern types of dewaxing processes the same procedure as to preliminary treatment is adhered to. In the Bray patents, of which No. 1,949,989 is typical, residual oil is deasphaltized by preliminary treatment with propane at elevated temperature before being dewaxed. In the IGF English Patent No. 389,113 the same procedure is followed. In the Standard Oil French Patent No. 739,264 and English Patent 409,110, the operation is described as applied to the separation of the paraffin from a distilled and treated lubricating oil which has been obtained from

crude Mid-Continent petroleum. In the Voorhees Patent 1,862,784, the wax bearing oil is referred to as a "treated wax bearing overhead lubricating cut". In the Giles Patent 1,943,236, the charging stock is referred to as a "residual treated steam refined oil or it may be an overhead lubricating stock". In Haylet Patent 1,968,392 acid treatment and dewaxing are carried out in propane solution with the acid treatment before the dewaxing stage. In the Tears Patent 2,000,427, high melting point wax is produced by cold settling under pressure from petrolatum stock, which is a "filtered or partially decolorized product". In Tears Patent 2,008,570, it is stated "by extreme decolorization and removal of crystal forming inhibitors removed by decolorization, filterable wax may be formed". In the Tears Decolorizing and dewaxing petroleum lubricating oils Patent 2,008,569, an outline of conventional refinery practice is given, wherein it is stated that the heavier cylinder stocks or steam refined stocks and long residuum are decolorized before dewaxing. These references show that in the present state of the art the charging stock to known dewaxing processes is subjected to some sort of preliminary treatment before dewaxing.

It has now been established that by modification of the operations described in Tears Patents Nos. 2,000,427 and 2,008,570, including changes in the proportion of solvent to oil before the pressure is applied for settling, residual lubricating oil stocks may be handled without preliminary treatment and with the surprising advantage that the dewaxed oil produced from the operations is largely decolorized.

The wax produced from the operation is of extremely dark color because of the color bearing constituents of the original oil accompanying the settled wax.

As an example of the operation, a charge of regular Pennsylvania steam refined stock having a viscosity of 140 seconds at 210° F. Saybolt was dewaxed without prior decolorization. The dewaxed oil represented 80% of the original charge and had a pour test of 0° F. The color of the dewaxed oil in 5% naphtha dilution was 4½ N. P. A. while the original charging stock in 5% naphtha dilution had a color of 6½ N. P. A. It is estimated that 75% of the color reduction required to make a 7½ N. P. A. color bright stock was accomplished in this dewaxing operation. The cast of the oil was also somewhat better than the usual soft Pennsylvania bright stock cast. The wax separated in the operation had a melting point of 119.2 A. S. T. M. and a dark brownish color. It

had practically none of the usual Pennsylvania lubricating stock cast. The viscosity of the wax product was 131 at 210° F. Saybolt, further indication of the segregation of color constituents with the wax layer, since the usual grade of 118-120 melting point Pennsylvania petrolatum has a viscosity of about 105 at 210° F. Saybolt. In other words, combination of the color compounds with the wax results in a viscosity increase in the wax layer. An interesting point is that the Saybolt Universal viscosity at 210° F. of the dewaxed and partially decolorized oil shows an increase of from 10 to 15 seconds over that of the original charging stock. This viscosity is reduced again to that of the original charging stock when the dewaxed and partially decolorized oil is decolorized to finished color.

Another interesting and desirable result is in the fact that the flash test of the undecolorized charging stock was 550° F. open cup, while the dewaxed oil showed a flash of 560° F. and the wax product had a flash of 540° F. This proves that this method of operation has distinct advantages in the improvement of the viscosity flash relationship of the finished oil. The usual grade of 140 viscosity bright stock has a flash of 545° F. to 550° F., but the product from this operation has a flash of 560° F. at the same viscosity.

Another proof of color constituent segregation with the wax product is found in the Conradson carbon residue of the charging stock, the dewaxed oil and the wax. Carbon residue of the original stock was 2.5, of the dewaxed oil 2.1, and of the wax 2.8. This proves removal from the finished oil of those compounds which serve to increase the carbon residue and which are removed by decolorizing filtration in conventional refinery practice. The yield of dewaxed oil obtained from the original charging stock compares favorably with that obtained from any other dewaxing process when producing oil of the same pour test.

The apparatus necessary and procedure are generally similar to those described in Patent 2,000,427 with the following exceptions:

(1) An exchanger 66 is provided for heat exchange between warm propane and the cold wax free oil and propane solution. The cold propane so produced is employed for replacing propane evaporated during the chilling stage and for restoring and increasing the solvent to oil ratio. The use of such exchanger of course reduces the load on the compression system and permits of a considerably lower operating cost.

(2) A different type of oil draw off arrangement is provided. In the new arrangement, a swing line carrying a sample line, is used instead of the fixed try cock and draw-off connections employed in the original process. This provides a more convenient and cheaper installation in that the multiplicity of valves is avoided. Also it enables closer separation between the oil and wax layers because the draw-off swing line can be moved to any desired level. The sample line being so located that it removes the sample right at the point of draw-off, permits close control of the point of withdrawal. In Patent 2,000,427, petrolatum is the charging stock and it contains from 25 to 75% of wax. When operating on residual stock, the wax content is only from 10 to 20%. This of course, results in a much smaller volume of the wax layer so the wax level is close to the bottom of the settlers.

The proportion of solvent to charging stock apparently is quite important and it appears that a larger solvent ratio than used in the original

process is required. Satisfactory results have been obtained with solvent to oil ratios during the settling stage within the ranges of 3.5 to 1 to 7 to 1. Higher solvent ratios than these probably would be effective.

The cost of decolorizing Pennsylvania steam refined stock to 7 1/2 N. P. A. bright stock color by conventional percolation filtration methods is from 2¢ to 3¢ per gallon. The cost of decolorizing the dewaxed and partially decolorized oil from this process to the same color bright stock is in the range of from 1¢ to 1 1/2¢ per gallon. This shows an important saving in the matter of cost of decolorization, particularly when it is considered that the amount of color removal obtained in this process is obtained at no cost.

It is probable that it would be impossible to centrifuge or filter the dark wax product from the chilled propane solution with equipment available in the art at present and that cold settling under pressure as employed in this process is the only manner in which it could be successfully removed. This is because of the unusually pasty or sticky consistency of the dark wax component which would rapidly clog either an ordinary filter or a conventional centrifuge bowl. It is conceivable however, that special filters or centrifuge machines or other mechanical separators could be developed to handle the separation of the wax and color bearing components and the invention comprehends any such form of separation. The addition of filter aid probably would make the mixture filterable and this type of separation is also comprehended.

The process has been practiced on Pennsylvania crude lubricating oil stocks which contain no or only relatively small amounts of asphalt and color bearing compounds. In applying the process to lubricating oils from other crudes such as Mid-Continent crude, it may be necessary to first remove a portion of the asphalt content until the asphalt and color bearing components are about in the same proportion as in the Pennsylvania stocks.

Apparently the success of this operation depends upon some affinity of the wax component for those constituents of the oil that serve to impart the color to the original oil. It may be that some of these color components are solid or semi-solid under the temperature conditions in the settling operation thus making it possible to separate them with the wax in the cold settling operation.

The range of temperatures to which the solution is to be chilled, which temperatures dictate the pressure to which the settling vessels are to be vented, depends upon the desired pour test of the finished oil. This temperature range may be from 0° F. to minus 45° F.

In the accompanying drawing, there is illustrated practical apparatus for carrying out the invention. It will be understood however, that this illustration is primarily for purposes of disclosure and that changes and modifications may be made all within the true spirit and broad scope of the invention.

Fig. 1 is a diagrammatic representation of the complete system.

Fig. 2 is a broken side elevation of one of the chillers showing in particular the adjustable swing line and sample line construction.

Fig. 3 is a broken end elevation of these same parts.

Fig. 4 is a broken perspective view of the offtake and sampling spout at the end of the swing line.

The complete combined operation is effected in the illustration as follows:

Normally gaseous liquid solvent such as propane, stored in tank 3, is mixed with undecolorized wax bearing oil from tank 4, by being transferred by pumps 5 and 6, through lines 7 and 8, through a mixer to a heater 9. This may be a steam coil heater which will raise the temperature of the mixture to 125° F. to 200° F., sufficient back pressure being maintained to hold the solvent in the liquid state by means such as back pressure valve 65.

The hot mixture is next cooled as by passage through a water cooler 10, and charged through lines 11, 12, 13, into the chillers and settlers 14, 15, 16, in parallel. In this charging operation, they may be filled to 80% of total volume under a pressure of approximately 150 lbs. per square inch, pressure sufficient to hold the propane in the liquid state.

The chillers and settlers are then slowly vented through lines 18, 19, 20, down to approximately atmospheric pressure, with the propane vapor passing off through line 21 to the suction side of the compressor 22, which is connected with condenser 23, to liquefy and return the propane to storage through line 24.

During the early stages of this cooling operation, relatively warm propane at a temperature which may range from 60° to 120° F. is introduced from storage tank 3, through lines 25, 26, 27. These lines are shown as entered down into the bottom of the chilling and settling tanks, so as to make this warm propane bubble up through the previously introduced oil solution. This accomplishes an agitation and thorough admixture and serves to maintain the liquid level up to or close to the original level. This admission of warm propane is continued during the chilling operation and until the temperature in the chillers and settlers is brought down to approximately 30° F. After this temperature has been reached, the desired high level is maintained by adding cold propane at a temperature of approximately 45° F., corresponding to atmospheric pressure, from cold propane storage tank 28 by pump 29 through lines 30—25, 26, 27.

The cold propane storage tank 28 in the illustration, is charged by expanding partially cooled propane from the exchanger 66, into it through lines 30a, 30b, 30c, from propane storage 3, under control of expansion valve 31. Propane vapor resulting from this refrigerating operation is taken off through lines 32—21 and compressed and condensed in the compression system heretofore described and represented at 22, 23.

The solution ratios may vary but the following may be considered as a desirable example: With chillers and settlers of a total full capacity of 10,000 gallons each, the liquid contained in each tank to 80% total volume would be 8000 gallons. The mixture of propane and undecolorized wax bearing oil charged into the tank to this level would then consist of 6000 gallons of propane and 2000 gallons of oil or a ratio of approximately 3:1. After the first chilling by evaporation and the addition of warm and then cold propane to further chill and bring the mixture up to the 80% volume level, this ratio of propane to oil remains the same but the temperature of the charge has been reduced to approximately 45° F., which corresponds to atmospheric pressure.

The chillers are then shut in and filled to full capacity, in the example, 10,000 gallons, with cold propane from tank 28 through pump 29 and lines

30—25, 26, 27. This pump may be continued in operation until pressure on the chillers reaches approximately 60 lbs. whereupon these chilling and settling tanks may be shut in under such pressure (60 lbs.) with a temperature of 45° F. In this closed state, the amount of propane has been increased to 8000 gallons, while the amount of oil remains the same, 2000 gallons, resulting in an increased ratio of propane to oil mixture of 4 to 1. The stirring or agitation of the mixture by entry 10 of the warm and the cold propane and the boiling due to evaporation results in or creates a practically perfectly uniform mixture of oil in propane and solid or semisolid wax and color bearing components ready to settle.

A settling period of from 1 to 4 hours is usually sufficient for the wax and color component content of the solution to drop to the bottom of the tank, the bright stock remaining in solution in the propane as a definite layer above the wax and color layer.

The precipitation of the wax and color results in a much lower propane to wax and color compound ratio in the bottom layer.

In the example under consideration, this may be a 1 to 1 ratio involving 400 gallons of propane and 400 gallons of wax and color, leaving an upper clear liquid layer containing 7600 gallons of propane and 1600 gallons of bright stock, a propane to oil ratio of about 4.8 to 1.

The chilling of the tanks by venting to the compressor through lines 18, 19, 20, 21, is preferably gradual, being carried out in the example over a period of not less than two hours. This is because shorter chilling time results in slower and less complete and definite settling of the wax and color component layer.

The adjustable swing line, carrying with it the sample line affords a practical and convenient means for quickly and accurately determining the level of separation between the oil and the wax-color component layers. This structure is shown in detail in Figs. 2 and 3, at the first chiller, where the swing line is indicated at 68, rotatably mounted in the stuffing box head 69, and having an angled inner end terminating in a take-off about 70, and its outer end rotatably coupled at 71, to the stationary take-off line 34.

The sample line is indicated at 72, carried by or incorporated in the swing line and as having a valved discharge 73, at the outer end. The off-take spout 70 is shown in Fig. 4 as thinned down toward a plane substantially radial to the axis of rotation to provide a narrow inlet, which will be substantially parallel with all different levels of liquid, enabling a more or less fine discrimination in all liquid level adjustments. This thinned spout is illustrated as widened along the axis parallel to the axis of rotation to give it the full capacity of the pipe. The sample line is indicated as terminating centrally of the mouth of the spout so as to give an accurate sample right at the center of withdrawal.

A hand lever 74 is shown provided on the exposed portion of the swing line carrying a screw clamp 75, cooperable with a quadrant 76. This handle serves both as a medium for adjusting and securing the swing line and in conjunction with quadrant 76, as an indicator for showing the position of the swing line within the tank, the quadrant, if desired, being laid off in suitable indications of angle, height, volume, or other values.

The swing lines are indicated as equipped with valves 77, and the draw-off lines with valves 78, 79.

by which they may be appropriately controlled.

After determining the level of the combined wax and color bearing component layer and setting and securing the swing line at the proper angle to take off the oil above this layer, the oil layer may be withdrawn down to the wax-color bearing component layer level through the swing line 68, and the lines 34, 35, 36 and pump 37 to the oil stabilizer 38, passing through exchanger 66, where it is in heat exchange relationship with warm propane going to the cold propane storage tank 28.

The reduction of the propane to wax-color compound ratio in the lower layer to approximately 1 to 1, makes this mixture somewhat difficult to handle, it being so thick and pasty that it can not ordinarily be pumped. Therefore, after drawing off the clear oil solution, the waxy mixture may be heated as by coils 39, in the bottoms of the tanks. This generates pressure in the chillers by vaporization of remaining propane therein until the pressure exceeds that at which the wax stabilizer is operated. This stabilizer is indicated at 44, Fig. 1 and its normal operating pressure may be 150 lbs. To overcome this, the chillers and settlers would be heated in the illustration to generate a pressure of approximately 225 lbs. at which pressure the entire wax color bearing component layers with accompanying propane will discharge through lines 25, 26, 27—45 into the wax stabilizer.

The oil stabilizer 38 and wax stabilizer 44, are shown as connected at the top by a vapor line 46, running to the discharge side of the compressor 22 and into condenser 23 and whereby the propane vapor is condensed and returned to the storage tank 3.

The heat required for stripping the propane from the oil and the wax color bearing components is supplied in the illustration by steam coils 47, 48, in the bottoms of the stabilizers and the oil and wax and color components from these two stabilizers are shown as discharged through lines 49, 50 into the oil and waxy strips 45 pers 51, 52, having top propane vapor connections 53, 21, to the suction side of the compressor and oil and wax and color compound delivery bottom connections 54, 55.

The oil and wax strippers 51, 52, are shown heated by steam coils 56, 57 and serve to remove the last traces of propane from the oil and wax and color bearing component taken from the bottoms of the oil and wax stabilizers. These strippers are operated at the pressure existing 55 in the suction line of the compressor, which may be 0 to 15 pounds gauge pressure.

The oil and the wax and color bearing components freed of solvent are indicated in the illustration as passed through lines 54, 55, from the strippers 51, 52, to storage by way of pumps 58, 59, and the oil and the wax coolers 60, 61.

Complete settling of wax and color bearing compounds can be effected in the relatively short period from 1 to 4 hours, after chilling. During the chilling, the mixture ratios are controlled by additions of warm and cold propane to restore the original ratio and finally to increase it before settling. By carrying out the settling under pressure of approximately 60 lbs. per square inch, the distinction between the wax and color bearing compounds and oil layers is definite and complete enabling production of practically wax free oil with the major portion of the color components also removed.

While the process involves batch operation, the

system may be developed into alternate use of the chilling and settling chambers, so as to gain continuous or semi-continuous operation. This is feasible particularly because of the relatively short chilling and settling periods required.

The application of the pressure for cold settling by pumping the chillers full is advantageous, but as an alternative, pressure may be applied in other ways and without necessarily pumping the tanks full. By way of example, a line 62, 10 is shown extending from the top of the propane storage tank 3, branched at 63, to the several chilling tanks and suitably valved at 64, enabling application of pressure from the propane storage tank for setting with the chilling and settling chambers less than completely full and possibly at different selected levels.

Instead of chilling the mixture by evaporation of a portion of the solvent as above described, the refrigeration may be accomplished by indirect means. In this mode of operation the tanks may be completely filled with the propane oil solution and then chilled by utilizing the coils in the bottoms of the tanks as chilling surfaces.

If indirect chilling is employed, the oil to propane ratios, after chilling to -45° F., would preferably be approximately the same as those in the above given example and the settling would result in the same ratios in the oil and wax color bearing component layers.

While propane serves as a particularly satisfactory solvent and diluent, it will be appreciated that other solvents of like character may be employed and that the use of this and other terms in the description of the example above is not by way of limitation, except as that intent is clearly indicated.

What is claimed is:

1. The herein disclosed process of dewaxing and partially decolorizing a previously untreated lubricating oil stock containing nonasphaltic color bodies substantially similar in nature to those present in Pennsylvania steam refined stock which comprises dissolving said untreated residual lubricating oil stock in liquefied normally gaseous hydrocarbon under pressure, chilling the mixture to below wax solidification temperatures while maintaining substantially the original ratio of solvent to oil and separating the wax and color bearing components in a combined state from the mixture.

2. The herein disclosed process of dewaxing and at the same time partially decolorizing an untreated residual lubricating oil stock, which comprises mixing a color bearing undecolorized stock which has not previously been subjected to decolorizing or acid treatment in liquefied normally gaseous hydrocarbon under pressure, chilling the mixture to below wax solidification temperature and batch cold settling the wax and color bearing components from the chilled mixture under pressure above the normal vapor pressure of the solvent at the temperature of the chilled mixture.

3. The herein disclosed process of dewaxing and at the same time partially decolorizing an untreated residual lubricating oil stock, which comprises mixing a color bearing undecolorized and otherwise untreated residual lubricating oil stock with liquefied, normally gaseous hydrocarbon under pressure, heating the mixture under pressure sufficiently to effect complete solution, cooling the mixture under pressure to remove the heat introduced for mixing and dissolving purposes, gradually releasing the pressure to vapor-

ize sufficient of the solvent to chill the mixture to below wax solidification temperature, adding liquefied normally gaseous hydrocarbon in sufficient volume to substantially maintain the original solvent ratio while so reducing the pressure and increasing the solvent ratio after chilling, and cold settling from the mixture the wax and color bearing components under pressure above the normal vapor pressure of the solvent at the temperature of the chilled mixture.

4. The process of claim 1 in which chilling of the mixture is effected by evaporating part of the liquefied normally gaseous hydrocarbon and in which solvent evaporated is at least partly replaced by cold solvent and in which cooling of the latter is effected by heat exchange with the chilled oil solution from which the wax and color bearing components have been separated.

5. The process of claim 3 in which the added

liquefied normally gaseous hydrocarbon is cooled by heat exchange with the chilled oil solution from which the wax and color bearing components have been settled.

6. The process of claim 1 in which the separation of wax and color bearing components from the mixture is accomplished by batch cold settling under pressure in excess of the normal vapor pressure of the solvent at the temperature of the chilled mixture.

7. The process as in claim 2 in which the cold settling under pressure is effected in a closed vessel and in which the oily layer is first withdrawn from the vessel and heat is then applied to the wax and color bearing constituent layer to generate sufficient pressure in the vessel to expel said layer from the vessel.
